CLAIM

The ornamental design for the partition panel for office cubicle, as shown and described.

DESCRIPTION

FIG. 1 is a top, front, right side perspective view of a first embodiment of a partition panel for office cubicle in accordance with my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged partial cross-sectional view of the partition panel for office cubicle shown in FIG. 2 taken along line 8-8;

FIG. 9 is similar to FIG. 1 and shows in broken lines one possible environment for the partition panel for office cubicle when integrated with another panel;

FIG. 10 is a top, front, right side perspective view of a second embodiment of a partition panel for office cubicle in accordance with my design;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is an enlarged partial cross-sectional view of the partition panel for office cubicle shown in FIG. 11 taken along line 17-17; and,

FIG. 18 is similar to FIG. 10 and shows in broken lines one possible environment for the partition panel for office cubicle when integrated with another panel.

The broken lines illustrate portions of the partition panel for office cubicle that form no part of the claimed design.

The dash-dot-dash lines shown in FIGS. 9 and 18 show possible environments for both embodiments of the partition panel for office cubicle and form no part of the claimed design.

1 Claim, 14 Drawing Sheets
